[57] CLAIM

The ornamental design for an infant carrier, substantially as shown and described.

DESCRIPTION

FIG. 1 is a perspective view of an infant carrier showing my new design;

FIG. 2 is a rear elevational view thereof;

FIG. 3 is a rear elevational view of the infant carrier with the hand straps in a carrying mode and the shoulder straps detached and folded in the storage pocket; and

FIG. 4 is a bottom plan view of FIG. 1.

The partial showing of shading indicating a fabric texture on the carrying straps in FIGS. 1, 2 and 3 is understood to be continuous throughout on all strap surfaces.
